UNITED STATES PATENT OFFICE.

GEORGE E. ST. JOHN, OF ADEL, GEORGIA.

RAIL BRACE AND CLAMP.

1,123,032.

Specification of Letters Patent. Patented Dec. 29, 1914.

Application filed June 19, 1914. Serial No. 846,170.

To all whom it may concern:

Be it known that I, GEORGE E. ST. JOHN, a citizen of the United States, residing at Adel, in the county of Berrien and State 5 of Georgia, have invented certain new and useful Improvements in Rail Braces and Clamps, of which the following is a specification.

This invention relates to a rail brace and 10 clamp.

The principal object of the invention is to provide improved means for releasably but securely connecting the rails with the tie and to prevent the rails from spreading.

Another object of the invention is to provide a fastening device which will be very strong and durable and not liable to slip 15 out of place when connected with the tie.

Another object of the invention is to provide a device which is very simple in construction and which may therefore be produced at a very small cost.

Another object of the invention is to so construct the device that the truss which 20 prevents the spreading of the rails will also provide means for assisting in holding the rail.

This invention is illustrated in the accompanying drawings, wherein—

Figure 1 is a side elevation of a tie provided with the improved rail securing means; Fig. 2 is a top plan view of the structure shown in Fig. 1; Fig. 3 is a bottom plan view of the structure shown in 25 Fig. 1; Fig. 4 is a view showing the tie and rail fastening means in end elevation with the rail shown in side elevation; Fig. 5 is a sectional view taken along the line 5—5 of Fig. 3; Fig. 6 is a perspective view of the 30 major jaw of one of the rail clamps; Fig. 7 is a perspective view of the auxiliary jaw which co-operates with the jaw shown in Fig. 6; and Fig. 8 is a sectional view taken along the line 8—8 of Fig. 4.

The rails 10 rest upon the tie 11 and are secured thereon by means of the improved securing device which forms the subject matter of this invention. These securing devices or clamps are connected by the rods 35 12 which are adjusted longitudinally by means of the turn buckle 13 so that the clamps may be held steady and thus prevented from any danger of movement which would permit the rails to spread. Nuts 14 and 15 are placed upon the truss rods 12 as 40 shown in Fig. 1 and form abutments and

securing means, the purpose of which will be hereinafter brought out.

From an inspection of the drawings it will be readily seen that these clamps are 60 duplicates and therefore a description of one of these clamps will suffice for both.

In Fig. 6 there is shown the main section or jaw of this clamp and from an inspection of this figure it will be readily seen that the main section or jaw comprises a head 16 in which a bolt opening 17 is formed and from which there extends an arm or bar 18 provided with bolt receiving openings 19. This main jaw is placed against the tie and 65 is secured to the same by means of bolts 20 which pass through the bolt receiving openings 17 and 19. A tongue 21 extends upwardly as shown in Fig. 6 and overhangs the head 16 so that it will engage the base 70 and web of the rail, when in a position as shown in Fig. 1. A finger 22 extends from the head 16 and is provided with bolt receiving openings 23 through which the securing bolt 24 and truss rod 12 pass. 75

After the major jaw has been secured to the tie by means of the bolts 20 the auxiliary jaw shown in Fig. 7 and designated by the number 25 is put in place with its tongue 26 engaging the base and web of the rail as 80 shown in Fig. 1 and its finger 27 engaging the finger 22. The bolts 24 are now passed through the upper openings 23 formed in finger 22 and upper openings 28 formed in the fingers 27 and the center bolt 20 is then 85 passed through the bolt receiving opening 29 which registers with the center bolt receiving opening 19 of bar 18. The truss rods 12 are now passed through the lower openings 23 and 28 of the fingers 22 and 27 90 and the nuts 15 are then placed upon the outer ends of the truss rods and the nuts 14 and 15 turned to move them into tight engagement with the fingers, thus securely 95 clamping the fingers together. After the 100 nuts 14 and 15 have been turned tightly into place the turn buckle 13 is turned to tighten the truss rods and place the same under tension, thus forming a very strong brace which will prevent any danger of the 105 clamps being broken or loosened thus permitting the rails to spread. When it is desired to remove one of the rails for any purpose it is simply necessary to remove the truss, bolt 24, and the center bolt 20. The 110 auxiliary jaw will then be free and may be removed, thus releasing the rail and permit-

ting it to be removed and a new one put in place without it being necessary to remove the major jaw.

What is claimed is:—

- 5 1. A tie, clamps connected with said tie, each of said clamps comprising a major jaw having a head, an arm extending from said head along said tie, means passing through said head and arm and connecting said major jaw with said tie, a tongue extending from said head to engage a rail, a finger extending from said head and provided with fastener receiving openings, an auxiliary jaw provided with a tongue for engaging a rail and with a finger engaging the finger of said major jaw and provided with fastener receiving openings registering with the fastener receiving openings of said first mentioned tongue, a fastener passing through said auxiliary jaw and through the arm of said major jaw and through said tie, fasteners passing through certain of the registering openings of said fingers, and a rod passing through the remaining registering openings of said fingers and provided with adjustable abutments engaging said fingers.
- 10 2. A securing device for a pair of rails comprising clamps having jaws provided with fingers having registering openings

formed therein, securing means passing through certain of said openings, and bracing means passing through the remaining openings and assisting in holding the jaws of said clamps in an operative position.

35

3. A securing device for a pair of rails comprising clamps each having a head, an arm extending from said head, a tongue extending from said head, a finger extending from said head, an auxiliary jaw fitting against said head and arm, a tongue for said auxiliary jaw, a finger for said auxiliary jaw engaging the finger of said major jaw, securing means releasably connecting said fingers, and bracing means for said clamps passing through the fingers of said clamps.

40

4. A securing device for a pair of rails comprising clamps having jaws provided with fingers, fastening means connecting said fingers, and bracing means for said clamps engaging said fingers to assist in holding the jaws of said clamps in an operative position.

45

In testimony whereof I affix my signature 50
in presence of two witnesses.

GEO. E. ST. JOHN.
